SEMIAUTOMATIC SCREW-DOWN CONTROL FOR ROLLING MILLS

George H. Rendel, Pittsburgh, Pa., assignor to United States Steel Corporation, a corporation of New Jersey

Application August 6, 1952, Serial No. 302,925

11 Claims. (Cl. 80—56)

This invention relates to a semiautomatic control for the screw-down motors in hot strip rolling mill stands.

In the steel making art a hot strip mill comprises a plurality of roughing and finishing roll stands which are adapted to act in tandem on steel strips previously heated to a suitable hot rolling temperature. Each roll stand is equipped with screws which control the separation between its rolls and screw-down motors for turning these screws up or down. One difficulty encountered in the operation of the finishing stands is that the rolled product becomes thicker nearer its trailing end than elsewhere, sometimes by as much as 8 to 10 percent. These heavy ends, known as "mill run-downs," are tapered and normally begin to appear approximately 100 to 200 feet from the trailing end of each strip.

The main factors which cause mill run-downs are believed to be loss of tension in the strip as its trailing end leaves each roll stand and the lower temperature on the strip near its trailing end. It is recognized that substantial savings would be realized by eliminating or minimizing mill run-downs.

An object of the present invention is to provide an improved means and method for reducing hot mill run-downs by automatically turning down the screws on a roll stand as the trailing end of a strip approaches the stand and thereby compensating for the factors which cause run-downs.

A further object is to provide a semiautomatic control for screw-down motors, which control automatically operates first to turn down the screws as the trailing end of each strip approaches a roll stand and subsequently to reset the screws after the trailing end exits from this stand.

Further objects are to provide such a control which has means automatically preventing its interfering with normal operation of the screw-down motors and which optionally can have a variable temperature compensating means.

In accomplishing these and other objects of the invention, I have provided improved details of structure, a preferred form of which is shown in the accompanying drawings, in which:

Figure 1 is a schematic side elevational view of a series of roll stands of a hot strip mill to which the control of the present invention is applied;

Figure 2 is a wiring diagram of the control; and

Figure 3 is a wiring diagram of a modification.

When the control of the present invention is applied to roll stands other than the first of a series, a convenient reference point from which to operate the control is the exit of the trailing end of each strip from a preceding stand. The control operates electrically, and I have illustrated a circuit which is set up by the entry of each strip to the roll stand two ahead of stand thus controlled and which is actuated by the exit of the strip from this same stand. However, it is apparent that equivalent results can be obtained with other means preceding the controlled stand for registering the passing of the trail-

2

ing end of each strip, for example, a photoelectric cell or a mechanically actuated switch located a proper distance ahead of the controlled stand. This distance can be determined in accordance with the characteristics of any strip being rolled.

Figure 1 shows schematically three finishing stands 10, 12 and 13 of a hot strip mill. Each stand includes work rolls 14 and screws 15 for regulating the separation between these rolls. In Figure 1 the first stand 10 is the reference stand, and the control is applied to the third stand 13, but it is apparent that similar controls can be applied to as many other stands as desired. Stand 10 is shown as having a D. C. drive motor 16, while stand 13 is shown as having a reversible D. C. screw-down motor 17. The other stands have similar motors, but no showing is needed for an understanding of the invention. The motors are energized from D. C. lines 18 and 19. Strip P passes through the roll stands from left to right. Inasmuch as such mills per se without the control are well known, no more detailed description is deemed necessary.

In accordance with the present invention, the circuit to the drive motor 16 of the reference roll stand 10 contains a load relay W. When motor 16 idly drives the rolls 14 of stand 10, it draws comparatively small current. When a strip P actually is between these rolls, the strip resists their rotation; consequently the motor draws a much larger current to drive them. The relay W is adjusted to pick up (i. e. to be actuated) when the motor draws the larger current and to drop out (i. e. to be deactuated) when the motor draws only the smaller idling current. Relay W has a set of normally open contacts W₁ (i. e. make-and-break means), and as hereinafter explained, operates the semiautomatic control on stand 13.

The screw-down motors 17 of the controlled roll stand 13 can be operated to raise or lower the screws 15 by the usual master controller, not shown, and are thus operated to move said screws to their initial setting. In accordance with the present invention, the circuit to these motors includes additional normally open contacts D₁ which when closed complete a circuit for operating the motors to move the screws down, and additional normally open contacts U₁ which when closed complete a circuit for operating the motors to move the screws up. These contacts are in "down" and "up" relays of the control circuit, hereinafter described. A magnetic clutch 20 has its drive element connected to one of the screws 15 of the roll stand 13 and its driven element connected to a cam 21 of a gage limit switch 22 in the semiautomatic control. As hereinafter explained, the magnetic clutch is engaged when the screw-down motors are energized via the contacts D₁ or U₁ of the semiautomatic control, but otherwise is disengaged so that normal operation of motors 17 by their master controller does not interfere with operation of the semiautomatic control and vice versa.

Figure 2 shows details of a preferred circuit for operating the semiautomatic control. The drive motor of the controlled roll stand 13 is indicated at 23 and the load relay thereof at X. This load relay likewise has a set of normally open contacts X₁ (i. e. make-and-break means). The control circuit is energized from A. C. lines 24 and 25 and includes "down" and "up" relays D and U which contain the aforementioned contacts D₁ and U₁. The control circuit includes six additional relays Y, Z, A, B, C and S, a time delay relay TD, a gage limit switch 22 already referred to, electronic vacuum tubes 26 and 27, potentiometers 28 and 29, and a step down transformer 30. Relay Y has one set of normally open contacts Y₁ and one set of normally closed contacts Y₂. Relay Z has two sets of normally open con-

3

tacts Z_1 and Z_2 . Relay A has three sets of normally open contacts A_1 , A_2 , and A_3 . Relay B has six sets of normally open contacts B_1 , B_2 , B_3 , B_4 , B_5 and B_6 . Relay C has two sets of normally open contacts C_1 and C_3 and one set of normally closed contacts C_2 . Relay S has one set of normally open contacts S_1 . Time delay relay TD has one set of normally closed contacts TD_1 . Gage limit switch 22 has one set of normally closed contacts $22a$ and one set of normally open contacts $22b$.

A pair of conductors 31 and 32 are connected to lines 24 and 25 respectively. Conductor 32 contains a manual "on-off" switch 33 for the semiautomatic control. Conductor 31 contains a set of normally closed contacts 34, which are in the master controller for the screw-down motors 17. Whenever the operator uses the master controller to run the screw-down motors in either direction, contacts 34 open and thus automatically cut out the semiautomatic control. The coil of relay Y and the normally open contacts W_1 of the load relay W of the reference roll stand 10 are connected in series across conductors 31 and 32. Likewise the coil of relay Z and the normally open contacts X_1 of the load relay X of the controlled roll stand 13 are connected in series across these same conductors. When the leading end of a strip P enters the reference stand 10 and relay W picks up, relay Y also picks up. When the leading end of this strip enters the controlled stand 13 and relay X picks up, relay Z also picks up. It follows that relays Y and Z also drop out when the trailing end of the strip exits from the respective stands.

A conductor 35, which contains the normally open contacts Y_1 , connects one end of the coil of relay A with conductor 31. A conductor 36, which contains the normally open contacts S_1 and the normally closed contacts TD_1 , connects the other end of this coil with conductor 32. Thus when relay Y picks up and its contacts Y_1 close, they condition a current path through the coil of relay A from line 24 via conductors 31 and 35, the relay coil, and conductors 36 and 32 to line 25. A conductor 37, which contains the normally open contacts Z_1 , connects one end of the coil of relay S with conductor 31. The other end of this coil is connected to conductor 32. Thus when relay Z picks up and its contacts Z_1 close, relay S also picks up. Closing of contacts S_1 completes the previously conditioned current path through the coil of relay A, and this relay also picks up and closes its contacts A_1 , A_2 and A_3 . Closing of contacts A_1 seals in relay A around contacts Y_1 , since contacts A_1 are situated in a branch conductor 31a which is connected between conductors 31 and 35 and shunts contacts Y_1 . Closing of contacts A_3 seals in relay S around contacts Z_1 , since contacts A_3 are situated in a second branch conductor 31b which is connected between conductors 31a and 37 and shunts contacts Z_1 .

A conductor 38, which contains the normally open contacts A_2 , connects conductor 32 with one end of the coil of relay B. A conductor 39, which contains the normally closed contacts Y_2 , connects the other end of this coil with conductor 31. Closing of contacts A_2 conditions a current path through this coil from line 24, via conductors 31 and 39, the coil, and conductors 38 and 32 to line 25. At the stage where the strip is passing through both roll stands 10 and 13, relay Y is energized and its normally closed contacts Y_2 are open, preventing completion of this current path. Summarizing, as long as the strip P continues to pass through both roll stands 10 and 13, relays W, X, Y, Z, A and S all are energized, relays A and S being sealed in; relay B is conditioned, but not yet energized; relays C, D, and U and time delay relay TD have not yet acted.

When the trailing end of the strip P exits from roll stand 10 and relays W and Y drop out, contacts Y_2 close and complete the previously conditioned current path through the coil of relay B, which thereupon picks up, and its normally open contacts B_1 to B_6 all close. Closing

4

of contacts B_1 seals in relay B around contacts Y_2 , since contacts B_1 are situated in a branch conductor 31c which is connected between conductors 31 and 39 and shunts contacts Y_2 . A conductor 40, which contains the normally open contacts Z_2 and B_2 , connects one end of the coil of relay C with conductor 31. A conductor 41, which contains the normally closed contacts $22a$ of the gage limit switch 22, connects the other end of this coil with conductor 32. Therefore closing of contacts B_2 energizes relay C, its effect being later described. A conductor 42, which contains the normally open contacts B_3 connects conductor 31 with one end of the timing element of the time delay relay TD. The other end of this element is connected to conductor 32. Therefore closing of contacts B_3 completes the circuit to the time delay relay which thereupon commences timing, its effect also being later described. The driving element of the magnetic clutch 20 is electrically connected to a current source 43, for simplicity illustrated as a battery, via conductors 44 and 45 which contain the normally open contacts B_4 and B_5 . Therefore closing these contacts engages the magnetic clutch and mechanically connects both the cam 21 and the slider of the potentiometer 28 with one of the screws 15 of the roll stand 13.

The normally open contacts B_6 are situated in conductor 32, which is connected to one end of the coils of both the "down" and "up" relays D and U for the screw-down motors 17 of the roll stand 13. The other ends of the coils of relays D and U are connected to the plates of tubes 26 and 27 respectively. The primary winding of transformer 30 is connected to lines 24 and 25; the secondary winding of this transformer energizes the filaments of both tubes via a pair of conductors 46 and 47. The cathodes of both tubes are connected to conductor 31 via conductor 47, and a conductor 48 which is connected between conductor 47 and the branch conductor 31a. Thus closing of contacts B_6 conditions a current path through the coils of both the "down" and "up" relays. For the "down" relay this current path is from line 24, via conductors 31, 31a, 48 and 47, tube 26, the relay coil, and conductor 32 to line 25. For the "up" relay the current path is similar except that it is via tube 27. It is seen that with the current paths thus set up, it is only necessary for one of the tubes 26 or 27 to become conductive for the relay D or U to pick up, close its contacts, and energize the screw-down motors 17.

For controlling the charge on the grids of tubes 26 and 27, the circuit includes a Wheatstone bridge 50 which contains the aforementioned potentiometers 28 and 29 and is energized by a current source 51, for simplicity shown as a battery. The slider of potentiometer 29 is adjustable manually beforehand to determine the distance the turn down screws are lowered by the semiautomatic control. The slider of potentiometer 28 is mechanically connected to the driven element of the magnetic clutch 20 as already mentioned. The left ends of the resistors of both potentiometers are connected to the positive battery terminal, with a variable resistor R_1 being interposed between potentiometer 28 and the battery. The right ends of the resistors of both potentiometers are connected to the negative battery terminals. A conductor 52 is connected between the slider of potentiometer 28 and one contact each of the normally open set C_1 and the normally closed set C_2 . The other contact of set C_1 is connected to the slider of potentiometer 29 via a conductor 53, while the other contact of set C_2 is connected to the negative battery terminal via a conductor 54. Conductor 52 contains two resistances R_2 and R_3 .

The grids of tubes 26 and 27 are connected to conductor 52 via resistances R_4 and R_5 respectively. In the starting position shown in Figure 2, which is before relay C picks up, no current flows through conductor 52, 54 since both ends are at the same negative potential. The grids of both tubes have a negative charge so that neither

tube is conducting. As already explained, relay C picks up when contacts B_2 close, whereupon its normally open contacts C_1 and C_3 close and its normally closed contacts C_2 open. Closing of contacts C_3 seals in the relay around contacts $22a$ of the gage limit switch 22, since these contacts are situated in a branch conductor $32a$ which is connected between conductors 32 and 41 and shunts contacts $22a$. Opening of contacts C_2 accompanied by closing of contacts C_1 unbalances the Wheatstone bridge, since there is a difference in potential between the point at which the slider of potentiometer 29 contacts the resistor thereof and the point at which the slider of potentiometer 28 contacts its resistor. Current now flows from potentiometer 29 through conductor 53, contacts C_1 and conductor 52 to potentiometer 28. The effect is to apply a positive charge to the grid of tube 26. Resistances R_2 and R_3 prevent application of a similar charge to the grid of tube 27.

Tube 26 becomes conducting, and the current path previously conditioned by the closing of contacts B_6 now is completed. The "down" relay D is energized and its contacts D_1 close, completing the current path to the screw-down motors 17 to lower the screws 15 of the controlled roll stand 13. Rotation of the screws rotates the cam 21, the magnetic clutch 20 being engaged. Cam 21 operates the gage limit switch 22 and opens its normally closed contacts $22a$ and closes its normally open contacts $22b$. Opening of contacts $22a$ has no immediate effect, since relay C is sealed in around them via its now closed contacts C_3 . Contacts $22b$ are situated in a branch conductor $36a$ which is connected between conductors 32 and 36 and shunts contacts TD_1 . After contacts $22b$ close, the time delay relay TD times out and its contacts TD_1 open, but relay A remains energized via contacts $22b$. Rotation of the screws also moves the slider of potentiometer 28 to the left across the resistor thereof. Ultimately it reaches a point where its potential is the same as that of the slider of potentiometer 29, whereupon the Wheatstone bridge again is in balance and current ceases to flow through conductor 52. The grid of tube 26 loses its positive charge and the tube ceases to conduct current. The down relay D drops out and the screw-down motors 17 stop. It is seen that the distance which the screws have been lowered before they stop is determined by the position of adjustment of potentiometer 29, since this adjustment determines the point at which the bridge comes into balance.

The screws 15 of the controlled stand 13 remain thus lowered until the trailing end of the strip exits from this stand and relays X and Z drop out. Contacts Z_2 open as the latter relay drops out and breaks the current path to the coil of relay C, which also drops out. The normally closed contacts C_2 again close and the normally open contacts C_1 again open. This action again unbalances the Wheatstone bridge 50, with the slider of the potentiometer 28 now being more positive than the conductor 54. Current now flows from potentiometer 28 through conductor 52, 54 in the opposite direction from its previous flow. The grid of tube 27 attains a positive charge and the tube becomes conducting. The previously conditioned current path through the coil of relay U has remained conditioned since relay B still is energized. When tube 27 becomes conducting, this current path is completed and relay U is energized, whereupon its contacts U_1 close and complete the current path to motors 17 for raising the screws. Resistances R_2 and R_3 prevent application of a similar positive charge to the grid of tube 26.

Rotation of the screws again rotates cam 21 and the slider of potentiometer 28, since the magnetic clutch 20 remains engaged, but rotates in the opposite direction from before. The potentiometer slider again reaches its original position at which the Wheatstone bridge is in balance and current flow ceases in conductor 52. The positive charge is removed from the grid of tube 27, 75

whereupon this tube ceases to conduct current and relay U drops out. The screw-down motors 17 thus stop with the screws back at their original setting. At the same time cam 21 operates gage limit switch 22 and returns contacts $22a$ to their normal closed position and contacts $22b$ to their normal open position. Closing of contacts $22a$ conditions the current path to relay C so that later it can pick up for the next strip. Opening of contacts $22b$ deenergizes relay A, whereupon its contacts A_1 , A_2 and A_3 open. Opening of contacts A_2 deenergizes relay B, while opening of contacts A_3 deenergizes relay S. Opening of contacts B_3 when relay B drops out deenergizes the time delay relay TD, and opening of contacts B_4 and B_5 disengages the magnetic clutch 20. Thus the semiautomatic control is fully reset.

From the foregoing description it is seen that the screw-down motors 17 on the controlled roll stand 13 automatically are operated to turn down the screws 15 as the trailing end of each strip approaches this stand. The distance which the screws are lowered is determined by the position of adjustment of the slider of the potentiometer 29, but once the adjustment is made, this distance is the same for all strips. Turning the screws down in this manner increases the pressure of the rolls 14 on the trailing end portion of the strip P and thus tends to reduce this portion to the same thickness as the remainder of the strip.

Figure 3 shows a modification in the Wheatstone bridge to regulate automatically the distance which the screws are turned down in accordance with variations in the temperature of the strip. It is desirable that the cooler the strip the farther the screws are turned down.

In Figure 3 two additional potentiometers 55 and 56 are connected in series between the positive terminal of battery 51 and the resistor of the potentiometer 28. The potentiometer 55 has a slider 57 mechanically connected to a pyrometer indicator, not shown, but which is responsive to the strip temperature. The pyrometer moves the slider in a direction to short out more and more of the resistor of the potentiometer the hotter the strip. The pyrometer automatically disconnects itself from the slider on attaining the maximum temperature of the strip. The potentiometer 56 is manually operated and regulates the degree of compensation for temperature. The less of the resistor that is shunted out in potentiometer 56, the more the temperature compensation. It is seen that the greater the resistance between the positive battery terminal and the potentiometer 28, the farther the slider of this potentiometer must travel to balance the bridge. Consequently the colder the strip, the greater the distance which the screws are turned down.

An example using hypothetical values may be helpful in understanding the temperature compensation feature. Assuming the voltage across the battery 51 is 100 volts and the voltage drop across the potentiometers 28, 55 and 56 is respectively 50 volts, 25 volts and 25 volts. If the strip being rolled is to have the maximum of compensation for temperature, the slider of the potentiometer 56 is adjusted so that the potential from the slider is 50 volts positive when referred to the negative battery terminal; that is none of the resistor of this potentiometer is shunted out. To balance the Wheatstone bridge, the screw-down motors must lower the screws until the slider of potentiometer 28 is at this same voltage. If the strip is so cold that the slider 57 of potentiometer 55 does not move to short out any of the resistor of this potentiometer, the voltage drop across potentiometer 28 remains 50 volts; the screws are lowered by an amount equal to the full travel of the slider of potentiometer 28. Full travel on this potentiometer may be equivalent to 0.100 inch vertical travel of the screws; therefore when the strip is cold, the controls lower the screws 0.100 inch and later return to their starting position.

If the strip is hot enough to move the slider 57 of po-

tentiometer 55 far enough to short out all of the resistor, the voltage drop across the potentiometer becomes zero. Now the voltage drops across potentiometers 28 and 56 are 66 $\frac{2}{3}$ and 33 $\frac{1}{3}$ volts respectively. The screws are lowered until the slider of potentiometer 28 reaches a position that is 50 volts positive. This position balances the bridge at a point where the slider is at 75 percent of full travel, which corresponds with 0.075 inch vertical travel of the screws.

If the strip being rolled is to have the minimum of compensation for temperature, the slider of potentiometer 56 is moved manually to shunt out all the resistance thereof. Now there is a voltage drop of 66 $\frac{2}{3}$ volts across potentiometer 28 and 33 $\frac{1}{3}$ volts across potentiometer 55. For the same setting on potentiometer 29 of 50 volts from its slider to the negative battery terminal, when a cold strip is rolled, the screw-down motors would lower the screws an amount equivalent to 75 percent of full travel of the slider of potentiometer 28 to balance the bridge. When the strip is hot enough to move the slider 57 of potentiometer 55 the full distance to shunt out all of its resistance, there would be 100 volts drop across potentiometer 28 and the slider of potentiometer 28 would move only have its full travel to balance the bridge.

This example shows how the control can be regulated from maximum to minimum temperature compensation by adjusting the slider of potentiometer 56. The total amount which the screws are lowered can be regulated by adjusting the slider of potentiometer 29. Preferably both potentiometers 56 and 29 are located where they are convenient to the mill operator.

While two embodiments of my invention have been shown and described, it will be apparent that other adaptations and modifications may be made without departing from the scope of the following claims.

I claim:

1. In a hot strip rolling mill which includes a plurality of roll stands, each of which has a pair of work rolls, a drive motor for said rolls, screws for regulating the separation between said rolls, and screw-down motors for turning said screws up and down, one of said stands being a reference stand and a succeeding stand being a controlled stand, the combination with said controlled stand of a semiautomatic control comprising load relays in the circuits of the drive motors of said reference and said controlled stands, each of said relays being adapted to pick up when a strip is between the rolls of its stand and otherwise to drop out, a control circuit connecting the load relay of said reference stand and the screw-down motor of said controlled stand for turning down the screws of the latter stand when the load relay of the former stand drops out as the trailing end of a strip exits therefrom, and means in said control circuit connected to the load relay of said controlled stand for resetting the screws thereof when this relay drops out as the trailing end of the strip exits from said controlled stand.

2. A combination as defined in claim 1 in which said control circuit includes a normally balanced Wheatstone bridge, connections between said bridge and the screw-down motor of said controlled stand for operating this motor when said bridge becomes unbalanced, connections between said bridge and the load relay of said reference stand for unbalancing said bridge when this relay drops out as the trailing end of a strip exits from this stand and thereby operating the screw-down motor of said controlled stand for turning down the screws thereof, and means for restoring the bridge to balance after the screws are turned down a predetermined distance.

3. A combination as defined in claim 2 in which the resetting means includes connections between said bridge and the load relay of said controlled stand for unbalancing said bridge when this relay drops out and means for restoring the bridge to balance when the screws return to their original setting.

4. In a rolling mill for lengths of hot strip having leading and trailing ends, which mill includes a series of roll stands each having a pair of work rolls, a drive motor for said rolls, screws for regulating the rolls separation and

75 power means for turning said screws up and down, said roll stands being adapted to roll a strip under tension and

thus tending to leave a tapered thicker portion in the strip near its trailing end, the remainder of the strip being of

substantially uniform thickness, at least one of said stands being a controlled stand, the combination with said con-

roll stands each having a pair of work rolls, a drive motor for said rolls, screws for regulating the roll separation, and power means for turning said screws up and down, said roll stands being adapted to roll a strip under tension and thus tending to leave a tapered thicker portion in the strip near its trailing end, the remainder of the strip being of substantially uniform thickness, at least one of said stands being a controlled stand, the combination with said controlled stand of a control for the power means for its screws effective to turn them down as the portion of a strip near the trailing end is between the rolls of this stand and up after the trailing end exits therefrom, but allowing the screws of the controlled stand to remain at settings attained independently of the control when the rest of the strip is between the rolls thereof, said control comprising a circuit connected with the power means for the screws of said controlled stand, a first make-and-break means in said circuit, means for actuating said first make-and-break means when the leading end of a strip passes a point located a predetermined distance ahead of said controlled stand and for deactuating said first make-and-break means when the trailing end passes said point, a second make-and-break means in said circuit, means for actuating said second make-and-break means when the leading end passes said controlled stand and for deactuating said second make-and-break means when the trailing end passes said controlled stand, means in said circuit conditioning a current path to the power means for the screws of said controlled stand when both said make-and-break means are actuated, means in said circuit completing this current path to operate said last mentioned power means to turn the screws down a predetermined distance when said first make-and-break means is deactuated, means for deenergizing said last mentioned power means after the screws are turned down said last mentioned predetermined distance, and means in said circuit completing a current path to operate said last mentioned power means to reset the screws when said second make-and-break means is deactuated.

5. A combination as defined in claim 4 in which said first make-and-break means and the actuating and deactuating means therefor include a load relay in the circuit to the drive motor of a roll stand preceding said controlled stand, and said second make-and-break means and the actuating and deactuating means therefor include a load relay in the circuit to the drive motor of said controlled stand, said relays picking up when a strip is between the rolls of the respective stands, but otherwise dropping out.

6. A combination as defined in claim 4 in which said circuit includes means for adjusting the predetermined distance by which the screws of said controlled stand are turned down on completion of the current path to the power means therefor.

7. A combination as defined in claim 4 in which said circuit contains a bridge across which the power means for the screws of said controlled stand is connected, said bridge remaining in balance when the circuit is conditioned, and means for unbalancing said bridge when said first make-and-break means is deactuated to turn the screws down and again when said second make-and-break means is deactuated to turn the screws up.

8. A combination as defined in claim 4 in which said circuit includes means responsive to strip temperature for automatically varying the predetermined distance by which the screws of said controlled stand are turned down in accordance with strip temperature.

9. In a rolling mill for lengths of hot strip having leading and trailing ends, which mill includes a series of roll stands each having a pair of work rolls, a drive motor for said rolls, screws for regulating the rolls separation and power means for turning said screws up and down, said roll stands being adapted to roll a strip under tension and thus tending to leave a tapered thicker portion in the strip near its trailing end, the remainder of the strip being of substantially uniform thickness, at least one of said stands being a controlled stand, the combination with said con-

trolled stand of a control for the power means for its screws effective to turn them down as the portion of a strip near the trailing end is between the rolls of this stand and up after the trailing end exits therefrom, but allowing the screws of the controlled stand to remain at settings attained independently of the control when the rest of the strip is between the rolls thereof, said control comprising a bridge circuit having arms which contain normally balanced adjustable resistances, electrical connections to the power means for the screws of said controlled stand connected across said bridge circuit and thus normally keeping this power means deenergized, a first make-and-break means connected to said bridge circuit, means for actuating said first make-and-break means when the leading end of a strip passes a point located a predetermined distance ahead of said controlled stand and for deactuating said first make-and-break means when the trailing end passes said point, a second make-and-break means connected to said bridge circuit, means for actuating said second make-and-break means when the leading end passes said controlled stand and for deactuating said second make-and-break means when the trailing end passes said controlled stand, successive actuation of both said make-and-break means conditioning said circuit and deactuation of said first make-and-break means unbalancing said circuit to energize the power means for the screws of said controlled stand to turn them down a predetermined distance, and a mechanical connection between one of the last mentioned screws and one of said adjustable resistances to restore said bridge circuit to balance and thus deenergize the power means when the screws are turned down said last mentioned predetermined distance, deactuation of said

5 10 15 20 25 30

second make-and-break means unbalancing said bridge circuit in the opposite direction to energize the power means for the screws of said controlled stand to reset these screws.

10. A combination as defined in claim 9 in which said mechanical connection includes a magnetic clutch normally disengaged to allow operation of the power means for the screws of said controlled stand independently of said control, and said control comprises a circuit for engaging said clutch when the power means is operated by unbalance of said bridge circuit.
11. A combination as defined in claim 9 in which said first make-and-break means and the actuating and deactuating means therefor include a load relay in the circuit to the drive motor of a roll stand preceding said controlled stand and said second make-and-break means and the actuating and deactuating means therefor include a load relay in the circuit to the drive motor of said controlled stand, said relays picking up when a strip is between the rolls of the respective stands but otherwise dropping out.
